UNITED STATES PATENT OFFICE.

LARS H. PYNTEN, OF BALTIC, SOUTH DAKOTA.

MORTISE AND MARKING GAGE.

SPECIFICATION forming part of Letters Patent No. 586,393, dated July 18, 1897.

Application filed July 15, 1896. Serial No. 599,257. (No model.)

To all whom it may concern:

Be it known that I, LARS H. PYNTEN, a citizen of the United States, residing at Baltic, in the county of Minnehaha and State of 5 South Dakota, have invented a new and useful Mortise and Marking Gage, of which the following is a specification.

This invention relates to a new and useful mortise and marking gage, and has for its object to provide a device of this description by means of which the guide-lines for the mortise or tenon may be inscribed and the marking-points of which may be adjusted with reference to an auger-bit, so as to transfer its 15 exact width to the material to be operated upon.

In some gages of ordinary construction the outside lines only are marked and the distance between the same is determined by 20 measuring with a rule, and in practice it is next to impossible to lay out lines by this method sufficiently accurate to permit the workman to bore a hole the full width of the mortise to be formed, thus necessitating considerable chiseling, which requires both time 25 and skill, and as no central line is provided which is accurate relative to the side lines it is a matter of guesswork to place the screw of the auger in the exact center of the side 30 lines, but by the use of my improvement not only are the side lines inscribed at the exact width apart of the diameter of the auger, but the central line is also inscribed at the same time, which facilitates the placing of the 35 starting-screw of the auger in its proper relative position to the side lines, and this is accomplished mechanically without calculation or measurement by the operator.

With these ends in view this invention consists in the details of construction and combination of elements hereinafter set forth, and then specifically designated by the claims.

In order that those skilled in the art to which this invention appertains may understand how to make and use the same, its construction and operation will now be described in detail, referring to the accompanying drawings, forming a part of this specification, in which—

50 Figure 1 is a side view of my improvement, showing it in operation; Fig. 2, a perspective thereof, illustrating its construction; Fig.

3, a detailed view of the three markers used in my improvement; Fig. 4, a section through the gage-block, illustrating the method of holding said block in its adjusted position; and Fig. 5 a diagrammatical view of the inscribed lines and auger placed in relation thereto, illustrating the manner of centering said auger by said lines.

55 Referring to the drawings in detail, A and B represent the two end blocks, in which are secured the guide-rods C, which are four in number, and journaled within the end blocks is a screw-rod D, which is provided with a 60 thumb-knob E, by which said rod may be turned upon its axis in either direction for the purpose hereinafter set forth.

The rod D is provided with right-handed threads F and left-handed threads G, between 65 which is a blank portion H, and the first-named threads pass through the threaded hub of the marking-disk I, and threads G likewise pass through the threaded hub of the marking-disk J, so that when the rod D is revolved, as before described, these marking-disks will be moved to and from each other, as the case may be and as is well understood 75 in the use of right and left handed screws.

The marking-disks have holes formed 80 therethrough for the passage of the guide-rods C, by which arrangement said disks are prevented from turning upon their axes and guided in their longitudinal movement. A stationary disk K is secured upon the guide-rods and has a central opening therethrough 85 for the passage of the screw-rod, and this disk is so located that the blank portion H of the screw-rod lies within its central opening.

90 The gage-block L is provided with holes for the free passage of the guide-rods C, and also a central hole M of sufficient diameter to permit the passage of the screw-rod D, and in order that this block may be held in any adjustment upon the guide-rods a set-screw N 95 is threaded therethrough, so that its end may bear against two of said guide-rods, and this screw is provided with a knurled head O to facilitate its operation. From this it will be seen that the gage-block may be adjusted and 100 held in any adjustment for the guidance of the marking-disks relative to the edges of the material to be operated upon, as shown in Fig. 1. The marking-disk I has two flattened

sections P, and the disk K one of such section Q, while the periphery of the disk J is a complete circle, so that when it is desired to inscribe only one line the device may be so turned as to cause the flattened portion Q of the disk K and one of the flattened portions P of the disk I to lie next the surface to be marked, thus cutting out the action of the disks I and K, but permitting the disk J to perform its function, and when it is desired to inscribe two lines the gage may be so turned as to cause one of the flattened portions P of the disk I to lie next the surface to be operated upon, while the marking edges of the disks J and K are permitted to act upon said surface.

A gage built in accordance with my improvement has many advantages, among which is the fact that it can be set by placing the marking-disks in conjunction with the auger or other boring-tools and operating the rod D, so as to bring said markers into alignment with the outer edges of said auger after the manner of gaging the diameter of a tool, when lines may be inscribed upon the surface to be operated upon, which will determine the width of the hole to be bored, and at the same time the central marker will inscribe a line midway between the two side lines, and this central line is of use in locating the auger, since the starting-bit of said auger may be placed thereon, and again when the gage has once been set for the mortise it may also be used for outlining the tenon, and the two will therefore exactly correspond, thus greatly reducing the time heretofore spent in laying out this class of work, as well as increasing the accuracy of the completed work. Another advantage of this arrangement is that when a tapering tenon is to be produced the central line inscribed by the marker K may be utilized to determine the pitch of the side lines relative thereto, thereby securing the same angle of taper upon both sides of the tenon.

In practice a gage built in accordance with my improvement operates more smoothly and accurately on account of the three markers acting at one time upon the surface of the wood, thereby overcoming the tendency of the grain to throw the marker out of line, since the three markers will not at one time fall upon grains of the same irregularity.

In assembling my improvement the markers are first screwed on the rod D, then the guide-rods passed through the holes in the markers, then the movable head L put on the rods, and, lastly, the blocks A and B are put on said rods and there held by clenching the ends of said rods, the blocks being countersunk to facilitate this operation.

The rod D is provided with a washer at either end thereof outside of the blocks A and B in order that it may be held against longitudinal movement within said blocks, the knob E being the last piece secured in place.

In practice I have found that a gage built in accordance with my improvement may be operated in half the time required for accomplishing the same work with other gages. 70

Having thus fully described my invention, what I claim as new and useful is—

1. A mortise and marking gage, consisting of guide-rods, end blocks to which said rods are secured, a screw-rod journaled within the end blocks, said rod having right and left handed threads formed thereon, adjustable marking-disks of different shapes adapted to slide upon the guide-rods and be actuated by the screw-rod, and a stationary marking-disk 75 80 located equidistant from the first-named disks, as specified.

2. In a mortise and marking gage, a series of guide-rods, end blocks to which said guide-rods are secured, a gage-block arranged to slide upon the guide-rods, a set-screw for holding said block in its adjusted position, a screw-rod journaled within the end blocks, said rod having right and left handed threads formed thereon, the disks I and J adapted to slide 85 90 upon the guide-rods, said disks having internally-threaded hubs for engagement with the threads upon the screw-rod, and a stationary marking-disk secured upon the guide-rods equidistant from the disks I and J, said disks 95 99 being of different shapes substantially as and for the purpose set forth.

3. In a gage of the character described, a series of guide-rods, end blocks for holding said rods parallel with each other, a threaded rod 100 105 D journaled within the end blocks, right and left handed threads F and G formed upon said rod, marking-disks I and J, each having an internally-threaded hub adapted to receive one set of the threads, a disk K secured upon the 105 110 guide-rods midway between the disks I and J, said disks being of different shapes, a knob E for operating the rod D, a gage-block adapted to slide upon the guide-rods, and a set-screw N for holding said block in any adjustment, substantially as shown and described.

4. In combination with the guide-rods of gages of the character described, the disks I, J and K arranged upon said rods, the disk I having two flattened portions, and the disk K 115 120 one flattened portion, substantially as and for the purpose set forth.

5. A gage having scratch-points composed of three disks slidable thereon, the first of said disks having two flattened portions in its perimeter and the second having one flattened portion in its perimeter registering with one of the flattened portions of the first disk, substantially as described. 120

In testimony whereof I have hereunto affixed my signature in the presence of two subscribing witnesses. 125
